UNITED STATES PATENT OFFICE.

WILLIAM H. DOANE, OF CINCINNATI, OHIO.

CENTERING DEVICE FOR TENONING AND OTHER MACHINES.

SPECIFICATION forming part of Letters Patent No. 328,391, dated October 13, 1885.

Application filed August 6, 1885. Serial No. 173,722. (No model.)

To all whom it may concern:

Be it known that I, WILLIAM H. DOANE, a citizen of the United States, residing at Cincinnati, in the county of Hamilton and State of Ohio, have invented certain new and useful Improvements in Centering Contrivances for Tenoning and other Machines; and I do hereby declare the following to be a full, clear, and exact description of the invention, such as will enable others skilled in the art to which it appertains to make and use the same.

It is quite important that the tenon, as well as the miter and throat of a spoke, be so cut that their axis or center line shall coincide with the axis or center line of the spoke. In practice it is found that spoke-blanks of a given size vary somewhat in thickness, so that in tenoning or mitering or throating a lot of spokes by machines heretofore known and used, the tenons and miters and throats of some of the spokes are cut more or less out of center.

The object of my invention is to remedy this objection to these machines.

To this end my invention consists of an automatic centering contrivance, which causes every spoke to be presented to the cutter-heads duly centered.

In order that my invention may be clearly understood I have illustrated in the annexed drawings, and will proceed to describe, a practical form thereof.

The drawings illustrate so much only of a spoke tenoning and mitering machine as will suffice to clearly exhibit the practical embodiment and application of my invention.

Figure 1 represents a front elevation. Fig. 2 represents a side elevation. Fig. 3 represents a plan view.

The same letters of reference indicate identical parts in all the figures.

A refers to the upper and B to the lower tenoning and mitering cutter-heads, which are constructed and mounted in the usual way. The spoke is centered and kept centered as it is fed through between the cutter-heads, by and between the knife-edge C' of a yielding lower jaw, C, and the knife-edge D' of a yielding upper jaw, D. The centering-jaws, pivoted by a pin, e, on a suitable standard, E, are

in this instance located in advance of the cutter-heads, and they project beyond them, so that their knife-edges may bite the spoke beyond the range of the cutters. The standard E has slots e' e' where it is bolted to the main frame or column of the machine, so that said standard can be adjusted to place the knife-edges of the jaws in proper position with reference to the cutter-heads. The knife-edges are made of sufficient length to seize the spoke before it reaches the cutter-heads, and to hold it until it has passed quite through between the cutter-heads.

Jaw C has a tail, C', and jaw D a tail, D'. These tails diverge and terminate in eyes, 65 through which a curved screw, F, passes loosely. The axis of the screw F is an arc struck from the center of pivot e, so that the tails of the jaws can move on the screw without binding. The curved screw is secured to a hanger, G, which is suspended from standard E by a pair of guide-bolts, g g, which engage a curved slot, g', in said hanger. The curve of slot g' is an arc struck from the center of pivot-pin e. Hanger G is provided with an adjusting-screw, H, which engages a fixed nut, e', on standard E, and by which the hanger may be adjusted along bolts g g. A clamping-bolt, g'', passing through a curved slot, g'', of the hanger into a screwed hole in standard E is provided to secure the hanger after it has been adjusted. Nuts f and f', on screw F, determine the normal distance between the knife-edges C' and D', which distance should be slightly less than the thickness of the spokes to be tenoned and mitered. The tails C' and D' are pressed against these nuts f and f' by the spiral springs I and I', the tension of which is adjustable by nuts f'' and f'''.

In feeding the spokes through between the knife-edges the centering-jaws are pressed apart more or less, according to the thickness of the spoke, in opposition to the springs I I', both jaws yielding practically alike, so that the spoke will be fairly centered.

It will be observed that the centering-jaws open and shut in a plane at right angles to the line of feed, while the knife-edges are parallel to the line of feed.

The centering contrivance would be oper-

ative without the adjustable hanger, but the presence of the latter is an advantage in facilitating the adjustments of the parts.

It is obvious that this centering contrivance is applicable to other wood-working machines where it is desirable to center the piece in passing it through between a pair of cutter-heads; also, that it can be used to so hold the spoke or piece that the cutter-heads will cut an eccentric tenon thereon, if that be required.

The parts C' and D' need not necessarily be knife-edges, because in the form of elongated bars they would operate fairly well; but I prefer to reduce their opposed edges to dull knife-edges, as shown and described.

I claim as my invention—

1. In a wood-working machine, a centering contrivance composed of a pair of jaws pivoted on the machine on an axis parallel to the line of feed, and a pair of elongated bars or knife-edges attached to the jaws parallel to the axis thereof, so that in use the jaws open and shut in a plane at right angles to the line of feed, while the knife-edges are parallel to the line of feed.

2. In a wood-working machine, the combi-

nation, substantially as before set forth, of the cutter-heads and the yielding centering-jaws, which are pivoted on the machine on an axis parallel to the line of feed, and which are provided with a pair of elongated bars or knife-edges extending alongside the cutter-heads.

3. The combination, substantially as before set forth, of the pivoted centering-jaws, the screw passing through openings in the tails of said jaws, a spring on one side of each of said tails, and an adjusting-nut on the said screw on the opposite side of each of said tails.

4. The combination, substantially as before set forth, of the pivoted centering-jaws, the adjustable hanger, the screw secured to the hanger, and passing through openings in the tails of said jaws, a spring on one side of each of said tails, and an adjusting-nut on the said screw on the opposite side of each of said tails.

In testimony whereof I affix my signature in presence of two witnesses.

WM. H. DOANE.
